UNITED STATES PATENT OFFICE.

ETHELBERT N. GILLING, OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

TANDEM STEAM HYDRAULIC APPARATUS.

1,407,146.

Specification of Letters Patent. Patented Feb. 21, 1922.

Application filed February 10, 1920. Serial No. 357,620.

To all whom it may concern:

Be it known that I, ETHELBERT N. GILLING, a citizen of the United States, and resident of Pittsburgh, in the county of Allegheny and State of Pennsylvania, have invented a new and useful Improvement in Tandem Steam Hydraulic Apparatus; and I do hereby declare the following to be a full, clear, and exact description thereof.

10 My invention relates to steam hydraulic intensifier apparatus such as used in connection with hydraulic presses, hammers, shears and the like. These presses have of late been desired of very large capacity, and a serious 15 problem has been encountered in developing sufficient power within a relatively small space because of the great size of the intensifier cylinder and the difficulty of maintaining the operating parts in proper working 20 condition where such tremendous power is developed, and of utilizing the press economically where such tremendous power is not required, for example, in forging operations where relatively smaller and lighter 25 forgings are to be produced, and where it is desirable to reduce the capacity of the press, at will.

In the accompanying drawings, Fig. 1 is a side view largely conventional of an apparatus embodying my invention; Fig. 2 is a longitudinal vertical section of the cylinders on the supply line of steam to the cylinders showing part of the piping in full line. Fig. 3 is a like view of the cylinder on a line 35 through the exhaust connections to the upper parts of the cylinder. Fig. 4 is an enlarged view partly in section of the main controlling valve and piping when supplying steam to both cylinders; and Fig. 5 is a 40 like view at an angle thereto when supplying steam to the lower cylinder.

My invention provides simple and convenient means for the development of a press of very large capacity and power for heavy 45 work; and where in the development of a single intensifier cylinder an excessively large cylinder would be required. By employing a main intensifier cylinder and an auxiliary intensifier cylinder, as herein generally described, both cylinders can be controlled by the same steam supply exhaust and other mechanisms as employed for a single cylinder, while by the provision of

an additional valve and piping, the auxiliary cylinder may be maintained in condition and 55 may be put into and out of operation as desired. The accompanying drawings illustrate a preferred embodiment of the invention, but it is to be understood that the invention is intended to be covered broadly 60 within the scope of the claims, and that various changes may be made in the details of construction and combination and arrangement of parts to that end.

The invention is illustrated in connection 65 with a forging press 1 having the stationary anvil or bed 2, the movable head 3 and the hydraulic press cylinder 4 with the lifting or pull back cylinders 5, these parts being of the usual or any desired construction. 70 The hydraulic main 6 extends from the hydraulic ram 7 of the intensifier while the usual pre-filler tank 8 and the fill-up and return valve 9 have maintained the cylinder 4 of the main forging press full of water or 75 other suitable liquid.

The invention is illustrated as having a single valve gear for controlling the operation of the intensifier in the development of power operating on the principle substantially such as shown in Letters Patent No. 813,209 granted to Thomas Edmund Holmes, February 20th, 1906, and also as shown in application for patent filed by Thomas W. Hand, on the 19th day of January, 1918, 85 Serial No. 212,550. In such valve mechanism 10 is the steam supply valve fed by the steam inlet 11, and 12 is the steam exhaust valve communicating with the main steam exhaust pipe 13, and the floating lever construction 14 disclosed in said patent and application is illustrated as controlled by the hand lever 15 and by the inclined bar 16 fixed to the movable member 17 of the hydraulic ram 7 of the intensifier and operating on 90 the bell crank lever 25. Any suitable form of main valve controlling mechanism may of course be employed.

The intensifier 18 is supported by the foundation plate 19 resting on the foundation 20 100 on which is supported the main steam cylinder 21 and above the same the auxiliary steam cylinder 22, and also the ram 7, the invention being illustrated as having the stationary member of the ram formed of the 105 ram cylinder 23 supported in the foundation

plate 19 while the movable member or plunger 24 is attached to and supported by the cross head 17. In the main cylinder 21 is the piston 27 to which is axially connected 5 the piston rod 28 which extends through the top plate 29 of the main cylinder and the bottom plate 30 of the auxiliary cylinder and is connected to the piston 31 of said auxiliary cylinder. The piston 27 of the main cylinder 10 is also shown as having the connecting rods 32 extending down through the bottom plate 33 of the main cylinder and connected to the cross head 17 carrying the ram plunger 24 above referred to. These parts are all suitably packed, as is usual in apparatus of this 15 type.

The upper ends of the main steam cylinder 21 and the auxiliary cylinder 22 communicate by continuously open ports 35 and 36 20 respectively, with the exhaust steam pipe 37 which leads down to the main exhaust steam pipe 13, the upper ends of the cylinders being thus always in communication with the main exhaust steam pipe. Steam is admitted 25 to and withdrawn from the lower or steam pressure side of the main cylinder piston 27 through the main steam inlet pipe 38 leading from the steam inlet valve 10 and exhaust valve 12 to the port 39 which communicates 30 directly with the lower part of the main steam cylinder 21. This pipe 38 then leads to the controlling valve 40 which controls the inlet and outlet of steam to and from the auxiliary steam cylinder 22 through the port 35 41 which leads through the pipe 42 to the lower or pressure side of the auxiliary cylinder piston, opening into the cylinder at 43. The control valve 40 (see Figs. 4 and 5) is formed of a casing 44 having the two center 45 diaphragms 45 and 45^a on each side of the port 41 leading to the upper or auxiliary steam cylinder. In this valve casing are also mounted the shells 46 and 47 in which shells is mounted the piston valve 50 having the 50 valve bodies 48 and 49. The shell 46 has a series of ports 51 communicating with the steam inlet pipe 38, and the shell 47 has a series of like ports 52 communicating with the steam exhaust pipe 37. When the combined piston valve 50 is in its lower position, 55 as shown in Fig. 4, steam passes from the main steam inlet 38 through the port 41 and pipe 42 into the lower or pressure portion of the auxiliary steam cylinder, the valve body 49 closing communication from that cylinder to the exhaust piping 37. When the combined valve 50 is raised, as shown in Fig. 5, the valve body 49 opens communication from the lower part of the auxiliary steam 60 cylinder 22 with the exhaust steam pipe 37. The valve 50 is operated by an independent valve 54 which may be of any suitable construction, such as an ordinary four-way valve having the pipe 55 leading to the upper end 65 of the valve casing 44 and the pipe 56 lead-

ing to the lower end of said valve casing, said valve 54 also communicating with the steam inlet pipe 57 and steam exhaust pipe 58.

In the operation of the machine where 70 both the main steam cylinder and the auxiliary steam cylinders are in use, through any suitable valve mechanism such as the valve mechanism illustrated, the supply and exhaust of steam is controlled by the main 75 steam inlet valve 10 and the main exhaust valve 12, the valve gearing being automatically controlled by the position of the hand 80 ing lever 15 and valve controlling mechanism 14, and the actions of the inclined or cam bar 16 on the control lever 25, and the steam is admitted through the steam inlet pipe 38 and the port 39 to the main steam cylinder 21 and then passes in its course through the valve body 40 and pipe 42 to the auxiliary steam cylinder 22. In this operation the upper parts of these cylinders are always in communication with the exhaust pipe 37 and the formation of a vacuum in the operation of the machine is prevented, 90 while any escape of steam around the pistons is taken care of. In such operation the piston valve 50 is in the position shown in Fig. 4 and connection from the lower side of the auxiliary cylinder to the supplementary exhaust pipe 37 and thence to the main exhaust is cut off. The feeding to and exhaust of the steam on the lower or steam pressure sides of the pistons 27 and 31 is through the steam inlet pipe 38 and then 100 forward to the main controlling valves.

Where it is desired to utilize the power developed only in the main intensifier cylinder 21, through the four-way valve 54, the piston valve 50 is raised to the position shown in Fig. 5 and the lower valve portion 48 closes communication from the main steam inlet pipe 38 to the upper cylinder, while the upper valve portion 49 is raised to provide communication between the lower 110 or pressure side of the auxiliary intensifier cylinder 22 and the auxiliary steam exhaust pipe 37. When the machine is so operated the piston 31 of the auxiliary intensifier cylinder is in balance, both sides being in communication with the auxiliary exhaust steam pipe 37, the upper part through the port 36 and the lower part through the port 43, pipe 42, piston valve 50 and thence to the pipe 37. At the same time, the upper part of the main 120 intensifier cylinder is in communication with the auxiliary and exhaust pipe 37 through the port 35. During this operation, the auxiliary intensifier cylinder is, however, maintained at the heat of the exhaust steam, 125 which under the stroke of the piston 31 is drawn into and out of the cylinder from the exhaust steam pipe 37, and the cylinder and its parts are maintained at the desired heat so as to hold the operative parts in full op- 130

erating condition, the undesirable effects of cooling and contraction being avoided and under control. As soon as the greater power is required, it may be during the operation 5 upon the same billet or bloom, the supplemental power developed in the auxiliary steam intensifier is added and operates in conjunction with the power developed in the main auxiliary cylinder, and through the main or 10 primary valve controlling apparatus. In such case the operation of the entire press with its full power is under the control of the handing lever 15 and the usual valve gear.

15 The advantage of my invention may be readily understood by those skilled in the art. By the simple manipulation of the valve 54 and through it the valve 50, the auxiliary intensifier may be put into and 20 out of operation as desired. When put into operation, the power of the intensifier may be practically doubled without changing the stroke of the press, and the apparatus is thus enabled to develop power which might 25 be impracticable on account of the great size of the intensifier cylinder where a single cylinder only was employed, and the operator is enabled to control both cylinders by the same handing lever. When the auxiliary cylinder is put out of use it is properly 30 balanced, and is maintained at the necessary heat by the exhaust steam to be in condition for instant operation in conjunction with the main intensifier cylinder. The 35 necessity for duplicating the valve mechanism is avoided and the machine is greatly simplified in construction and arrangement.

While in the drawings, I have shown the 40 ram of the intensifier cylinder as being underslung, it will be obvious that my invention is not limited to this particular arrangement, but the plunger of the ram may be connected to the intensifier piston in any known manner, and the above description of operation 45 would apply under the changed conditions.

I claim:

1. In a steam hydraulic intensifier, the 50 combination of a main intensifier cylinder, an auxiliary intensifier cylinder, a ram, pistons in said cylinders connected to the ram, valve mechanism for controlling the steam supply of both cylinders when operated together, and auxiliary valve mechanism for 55 cutting off the steam supply of one of said cylinders, whereby the latter may be put into or out of operation at will.

2. In a steam hydraulic intensifier, the 60 combination of a main intensifier cylinder, an auxiliary intensifier cylinder, a ram connected to the pistons of both cylinders, a common steam supply for both cylinders, valve mechanism controlling such supply, and auxiliary valve mechanism for controlling 65 the supply to one of said cylinders

whereby the latter may be put into or out of operation at will.

3. In a steam hydraulic intensifier, the combination of a main intensifier cylinder, an auxiliary intensifier cylinder, pistons in 70 said cylinders and connected together, a ram connected to the piston of one cylinder, a continuously open exhaust pipe communicating with the upper ends of said cylinders, a common steam supply pipe communicating 75 with the supply sides of both said cylinders, valve mechanism controlling the steam supply to both cylinders, and an auxiliary valve controlling the supply to said auxiliary cylinder.

4. In a steam hydraulic intensifier, the combination of a main intensifier cylinder and an auxiliary intensifier cylinder, pistons in said cylinders connected together, a continuously open exhaust pipe and continuously 80 open ports leading from the upper sides of said cylinders to said exhaust pipe, a common valve-controlled steam pipe communicating with the supply sides of both cylinders, and an auxiliary valve controlling 85 the supply to said auxiliary cylinder and forming communication from said cylinder, as desired, both to said steam pipe and to said exhaust pipe.

5. In a steam hydraulic intensifier, the 90 combination of a main intensifier cylinder and an auxiliary intensifier cylinder, a ram connected with the pistons of both cylinders, a common valve-controlled steam pipe communicating with the supply sides of both 100 cylinders, but directly with the main cylinder, a continuously open exhaust pipe and continuously open ports leading from the upper ends of both cylinders to said exhaust pipe, and an auxiliary valve acting to open 105 and close communication from said steam supply pipe to the supply side of the auxiliary cylinder, and to open and close communication from said supply side of said auxiliary cylinder to said exhaust pipe.

6. In a steam hydraulic intensifier, the combination with a main intensifier cylinder and an auxiliary intensifier cylinder, a ram connected to said pistons within said cylinders, a continuously open exhaust pipe 115 and continuously open ports leading from the upper side of said cylinders to said exhaust pipe, a steam supply pipe communicating with the supply side of the main cylinder, and a slide valve adapted to open 120 and close communication between the steam supply and the supply side of the auxiliary cylinder, and to open communications between the said side of the auxiliary cylinder and the exhaust pipe.

7. In a steam hydraulic intensifier, the combination of a main intensifier cylinder, an auxiliary intensifier cylinder, a ram connected with the pistons in said cylinders, a continuously open exhaust pipe and con- 130

tinuously open ports leading from the upper sides of said cylinders to said exhaust pipe, a steam supply pipe communicating with the supply side of the main cylinder, a 5 valve having a central opening leading to the supply side of the auxiliary cylinder, and having a slide valve body adapted to alternately close communication with the steam

supply pipe and with the said steam exhaust pipe.

In testimony whereof I, the said ETHELBERT N. GILLING, have hereunto set my hand.

ETHELBERT N. GILLING.
